FIG. 1 is a first perspective view of a shock end loop;
FIG. 2 is a second perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof; and,
FIG. 9 is a perspective view of the shock end loop affixed to
an adjustable shock member.
The broken lines are included for the purpose of illustrating
environmental features and form no part of the claimed
design.
